UNITED STATES PATENT OFFICE

LAURENCE A. KING AND HAROLD H. SHOTWELL, OF ST. CHARLES, ILLINOIS, ASSIGNEES
TO OPERADIO MANUFACTURING CO., OF ST. CHARLES, ILLINOIS, A CORPORATION OF
ILLINOIS

SOUND EMITTING DEVICE

Application filed November 1, 1929. Serial No. 404,091.

The invention relates to sound emitting devices, and more particularly to loud speakers adapted to be employed with radio-receiving sets, phonograph pick-up devices, sound picture apparatus, and the like.

A particular object of the invention is to provide devices of the kind described which are particularly adapted for theatre, or outdoor work, and combines desirable features 10 of an air-column speaker with those of an electro-dynamic speaker.

Fundamental frequencies as low as 50 to 70 cycles are reproduced in air-column speakers having reproducing units which comprise 15 metal diaphragms, and because of the power required to drive the higher frequencies through the long air-column, the low frequencies are predominant in the sound emitted from the sound passage.

One advantage of an air-column loudspeaker is that the sound is concentrated and directed in a specific direction, and because of this carrying power the various frequencies that are reproduced are substantially equal.

Another advantage is that all of the energy comes out of the mouth of the horn in the direction desired and no energy issues from the back of the speaker to cause disagreeable acoustical effects or loss of energy.

Frequencies from 50 up to 5000 or 6000 cycles are readily reproduced by an electro-dynamic cone type speaker which has been properly designed and is provided with a well designed baffle, but the characteristics of a speaker of this type are such that at a distance 50 feet away from the speaker the reproduction begins to thin out and only certain frequencies reach one under normal intensity. Another disadvantage of this speaker is that

40 equal amounts of energy are projected from the back and front of the diaphragm and the energy issuing from the back of the diaphragm tends to produce undesirable acoustical effects which are particularly noticeable in 45 theatre work.

Our improved speaker combines the advantages of the air-column speaker with those of the electrodynamic speaker in such manner that they combine for the advantages of each type. The improved speaker is of such 50 proportions that it may be readily positioned in back of a sound screen.

Many other objects and advantages will appear as this description progresses, reference being had to the accompanying drawings, wherein:

Fig. 1 is a front elevation of a loud speaker which embodies the invention;

Fig. 2 is a rear elevation of the improved speaker;

Fig. 3 is an enlarged section taken on line 60 3-3 of Fig. 1;

Fig. 4 is an enlarged section taken on line 4-4 of Fig. 1;

Fig. 5 is a perspective of one of a plurality 65 of clip devices for holding a screen in position over the mouth of the speaker; and

Fig. 6 is a front elevation of one of a plurality of arcuate members which co-operate with the clip devices to hold the screen in 70 position over the mouth of the speaker.

Referring to the drawings, the reference character 10 designates, generally, a speaker of the electro-dynamic type, the speaker 10 being provided with a diaphragm 11 which 75 comprises a conical portion 13. The conical portion 13 is apertured at its apex and secured to the conical portion at the aperture therein is a sleeve 15 which carries a coil or winding 16 adapted to be connected to the 80 output circuit of a radio-receiving set, phonograph pick-up, sound picture apparatus, or the like. The winding 16 is hereinafter referred to as the "voice coil".

At its larger end, the conical portion 13 85 of the diaphragm 11 is provided with an annular flange 18 which projects into an annular space provided between felt rings 19 and 20 carried by cardboard rings 21 and 22, respectively, the felt and cardboard rings 90

being mounted in a metallic ring 24 which is preferably secured to a supporting ring 26 by screws 27, or the equivalent.

The voice coil 16 is concentrically disposed in an annular magnetic gap 30 formed between a central pole piece 31 and an annular pole piece 32, the annular pole piece 32 being rigidly secured to a cup-shaped magnet member 34 which carries the central pole piece 31. Disposed around the pole piece 31 is a winding 36 which is connected by conductors 37 and 38 to any suitable source of direct current. Preferably, formed integral with the cup-shaped magnet member 34 are a plurality of radially extending arms 40 which carry the supporting ring 26 and are preferably formed integral therewith.

The opening in the front end of the speaker 10 is preferably closed by a screen 42 carried by a metallic ring 43 secured to the supporting ring 26.

As is well known to those skilled in the art, fluctuations in the current flowing in the voice coil 16 react with the annular magnetic field 30 and cause the voice coil and the diaphragm 11 to vibrate so that the fluctuations of the current in the voice coil are translated into sound.

The electro-dynamic speaker 10 is preferably mounted in the central opening of an annular member 46 which is preferably molded from plastic material and co-operates with a dished member 47 to provide an annular sound passage 48, the construction being such that the annular sound passage 48 has an annular mouth 49 encircling the annular member 46. The dished member 47 is also preferably formed from plastic material. The inner surfaces 50 and 51 of the annular member 46 and the dished member 47, respectively, are preferably formed in such manner that a section through the speaker on any diameter thereof appears to show two sound passages extending from the back or outer surface of the diaphragm 11 to diametrically disposed portions of the mouth 49. The construction is such that the surfaces 50 and 51 are more or less exponential, the actual curves of these surfaces being determined, to some extent, by the size of the speaker. It will be noted that the dished member 47 is preferably provided with a central projection 55 which has its outer ends disposed in close proximity to the apertured apex of the conical portion 13. Obviously energy projected from the back surface of the diaphragm 11 is projected through all parts of the sound passage 48 and issues from the mouth thereof. Energy projected from the front surface of the diaphragm 11 is projected in the same direction through the screen 42.

Disposed around the edge of the dished member 47 are metallic rings 57 and 58, and disposed around the outer edge of the annu-

lar member 46 are metallic rings 59 and 60. The rings 57, 58, 59 and 60 reinforce the dished member 47 and the annular member 46, respectively, and co-operate with a plurality of bolts 61 to support the annular member 46 concentrically with respect to the dished member 47. Thus, it will be noted that the bolts 61 are provided with a plurality of nuts 65 which may be manipulated to secure the members 46 and 47 in adjusted positions with respect to each other.

Additional means for supporting the annular member 46 concentrically with respect to the dished member 47 comprise a plurality of bolts 68 which project through the walls of the members 46 and 47 and are provided with nuts 69 which may be manipulated to secure the members 46 and 47 in adjusted positions with respect to each other.

The mouth 49 is preferably covered by a plurality of arcuate screens 70 which are held in place by means including a plurality of arcuate members 72, each of which is provided with a plurality of screw-threaded holes 73 (see Fig. 6). The outer edges of the arcuate screens 70 are preferably clamped between the arcuate members 72 and the front edge of the dished member 47, and the arcuate members 72 are secured in place by clip members 75 having slotted ends 76 adapted to be clamped between some of the nuts 65 and the ring 57. Screws 78, or the equivalent, project through the clip members 75 and are screw-threaded into the screw-threaded holes 73 provided in the arcuate members 72.

Similar means is provided for clamping the inner edges of the arcuate screens 70 to the annular member 46. Thus, we preferably provide a plurality of arcuate bars 80 which resemble the arcuate members 72, but are smaller in size. The inner edges of the screens are clamped between the arcuate bars 80 and the peripheral edge of the annular member 46. The arcuate bars 80 are held in place by clip members 81 which are preferably identical in construction with the clip members 75 and are held in place by having portions thereof clamped between the ring 60 and some of the nuts 65 provided upon the bolts 61. Screws 84, or the equivalent, secure the ends of the arcuate members 80 to the clip members 81.

As best shown in Fig. 1, we also prefer to provide a plurality of metallic straps 85 at the joint between the several screens 70, the ends of the straps 85 being preferably clamped between the clips 75 and 81 and the arcuate members 72 and 80.

Any suitable means may be provided for supporting the improved speaker, but we prefer to employ a base which is designated generally by the reference characters 87 and is preferably fabricated from a plurality of metallic straps or bars.

As best shown in Figs. 1 and 3, a U-shaped

bar 88 is positioned below the front end of the speaker, and as best shown in Figs. 2 and 3, a flat supporting bar 89 is provided at the back end of the speaker. The ends of a substantially V-shaped bar 90 are secured to the ends of the bar 89 and the central portion of the V-shaped bar 90 is secured to an L-shaped bar 93 by a bracket 94 (see Fig. 3). The L-shaped bar 93 is also secured to the bars 88 and 89 and to one of the bolts 68.

The conductors 37 and 38 leading from the terminals of the field winding 36 of the magnetizing structure, which comprises the pole pieces 31 and 32, preferably pass through an aperture 95 provided in the supporting ring 26 and having their outer ends connected to terminals (not shown) provided in a junction box 98 carried by the annular member 46. A cable 100 having suitable electrical conductors therein connects the terminals (not shown) in the junction box 98 with a power pack 101 carried by the base 87. The power pack 101 is provided if the field winding 36 is to be energized from a source of alternating current, and preferably comprises a step-down transformer and a rectifier. Of course, if the field winding is to be energized from a commercial source of direct current, it is not necessary to provide the power pack. It will be noted that the cable 100 passes through apertures 103 and 104 provided in the annular member 46 and the dished member 47, respectively.

The means for securing the electro-dynamic speaker 10 to the annular member 46 preferably comprises a metallic ring 110 embedded in a front edge of the annular member 46 and anchored to the annular member by a plurality of bracket members 111, the bracket members 111 being preferably embedded in the annular member during the molding operation. The aforementioned screws 27 are utilized to secure the supporting ring 26 to the ring 110.

It will be noted that the improved speaker shown in the drawings is relatively thin from the front surface to the back surface thereof. This construction enables it to be employed with advantage behind a sound screen when the space in back of the sound screen is rather small. Another advantage of the speakers embodying the present invention is that they have tremendous carrying power for air port or outdoor work, as they have a large wave-front.

The electro-dynamic speaker 10 is preferably of approximately the same size as electro-dynamic speakers now in general use in connection with radio-receiving sets, and therefore it is, in itself, large enough to be employed as a loud speaker in a relatively large room. The diameter of the dished member 47 is proportionately large, and we have obtained satisfactory results with speakers in which the dished members 47 are from 5 to

5½ feet in diameter. Of course, the wave-front is substantially the same diameter.

The annular member 46 functions both as a baffle between the front and back surfaces of the diaphragm and as a part of the means for amplifying the sound projected from the back surface of the diaphragm.

A feature of the invention is the provision of an electro-dynamic speaker in which the magnetizing structure is disposed substantially within the conical diaphragm. By positioning the magnetizing structure adjacent the inner or concave side of the conical diaphragm, the construction of our improved speaker is simplified as the energy projected from the back surface of the diaphragm is readily delivered into the sound passage 48.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as possible, in view of the prior art.

What we regard as new, and desire to secure by Letters Patent is:

1. A device of the kind described comprising a sound passage having an inlet end and terminating at the other end in an annular mouth, and a sound reproducing unit disposed at said inlet end, said sound reproducing device comprising a conical diaphragm having its outer or back surface arranged to project energy into said sound passage and having its inner or front surface arranged to project energy in substantially the same direction as said mouth.

2. A device of the kind described comprising an annular sound passage having an inlet end, and a sound reproducing unit disposed at said inlet end and comprising a diaphragm having one side arranged to project energy into said sound passage and having its other side arranged to project energy directly away from the device.

3. A device of the kind described comprising an annular member, a dished member forming a sound passage with said annular member and provided with a central lug projecting toward said annular member, and a reproducing unit carried by said annular member and provided with a conical diaphragm, the back or outer side of the diaphragm being arranged to project energy into said sound passage and the front or inner side of said diaphragm being arranged to project energy directly away from said device.

4. A device of the kind described comprising an annular member, a dished member, means for holding said members in spaced relation to provide a sound passage having

an annular mouth, a sound reproducing unit communicating with said sound passage, a plurality of arcuate screens for said mouth, and means for securing said screens to said annular and dished members.

5 5. A device of the kind described comprising a sound passage having an inlet end and terminating at the other end in an annular mouth, and a sound reproducing unit disposed at said inlet end, said sound reproducing unit comprising a diaphragm having one surface arranged to project sound into said sound passage and having its other surface arranged to project sound in substantially the same direction as said mouth.

10 6. A device of the kind described comprising a dished member, an annular member disposed in said dished member and co-operating therewith to form an annular sound passage, and a sound reproducing device carried by said annular member, said sound reproducing device having a diaphragm of which one side projects sound into said annular sound passage and of which the other side projects sound directly into the air in front of the device.

15 7. A device of the kind described comprising a dished member, an annular member disposed within said member, said dished member and said annular member co-operating to form a sound passage whereof the central aperture of said annular member is the inlet, and a sound reproducing unit disposed at said inlet, and provided with a diaphragm, one side of said diaphragm being adapted to project sound into said sound passage and the other side thereof being adapted to project sound into the air in front of said dished member.

20 40 In testimony whereof, we hereunto set our hands this 30th day of September, 1929.

LAURENCE A. KING.
HAROLD H. SHOTWELL.
